UNITED STATES PATENT OFFICE.

CHARLES WILCOCK, OF LEEDS, COUNTY OF YORK, ENGLAND, ASSIGNOR TO
MATTHEW ALFRED BRIGG AND DAVID DIXON, BOTH OF SAME PLACE.

APPARATUS FOR OILING RAGS.

SPECIFICATION forming part of Letters Patent No. 391,670, dated October 23, 1888.

Application filed June 30, 1887. Serial No. 242,967. (No model.) Patented in England March 10, 1887, No. 3,645.

To all whom it may concern:

Be it known that I, CHARLES WILCOCK, a subject of the Queen of Great Britain, residing at Leeds, in the county of York, England, 5 have invented certain new and useful Improvements in Apparatus for Oiling Rags, (for which I have obtained Letters Patent in Great Britain, No. 3,645, dated March 10, 1887,) of which the following is a full, clear, and 10 exact specification.

This invention has for its object to provide novel, simple, and efficient means for uniformly and mechanically dropping oil in a transverse line across a layer of rags, yarn, or 15 other fabric in its travel or passage to a rag pulling or opening machine.

To such end the invention consists in the features of construction and combination of devices hereinafter described and claimed, reference being made to the accompanying drawings, in which—

Figure 1 is a sectional elevation of an apparatus embodying my invention; Fig. 2, a top plan view omitting the strainer; and Fig. 3, a 25 front elevation.

In order to enable those skilled in the art to make and use my invention, I will now describe the same in detail, referring to the drawings, wherein—

30 The letter A indicates a tank, in which is placed warmed or heated oil, which is prevented from quickly cooling through the medium of a filling, C, of slag-wool, asbestos, or other substance that is a non-conductor of 35 heat interposed between the walls of the tank and an external surrounding jacket or case, B. The upper open end of the tank is fitted with a foraminous strainer-plate, K, for straining the oil of impurities and solid matters when 40 poured into the tank through such plate.

The letter G indicates a horizontal cylinder or pipe for distributing the oil to the oil-dropping nozzles H, which depend from the lower side of the cylinder and are arranged in a right line in close proximity to each other, so as to drop the oil uniformly in a right line transversely or across a layer of rags, yarn, or other fabric, which is caused to travel beneath the nozzles—as, for instance, by a support, I, carrying the rags and moving in the direction of

the arrows, Figs. 1 and 2, for delivering the rags or other fabric to a rag pulling or opening machine. The nozzles H are numerous for the purpose of dropping down a longitudinal line of oil-drops in close proximity to each other, and the nozzles have contracted mouths to insure the oil being discharged in uniform drops. The cylinder or pipe G is connected at several points to the tank by the pipes F, each having a cock or valve for controlling the flow of oil therethrough, and the inner open ends of the pipes preferably communicate with the oil through the medium of a chamber, D, located in the tank and placed in communication therewith by tubular elbows 55 E, whereby the oil first passes from the tank through the elbows into the chamber D, and from thence to the distributing cylinder or pipe through the valued pipes.

The use of several pipe-connections F between the cylinder and the oil is desirable for the purpose of more uniformly supplying the oil to the nozzles.

The chamber D, while preferred by me in practice, is not, however, essential, and may, 75 if desired, be omitted.

For the purpose of clearly indicating the oil-level in the tank, I provide a glass gage, J, made to communicate at its upper and lower ends. By the filling C, of slag-wool, asbestos, 80 or other non-conductor of heat, I obtain better results, in that the oil is kept warm. The oiling of the rags or other fabric, as set forth, places the same in proper condition to be readily pulled apart by the rag-machine, and 85 by this means longer fibers are obtained.

By arranging the several parts in the relation described and shown the layer of rags on the moving or traveling support or carrier is uniformly oiled in transit to the rag-pulling 90 machine; and, moreover, the oil dropping by gravity down upon the rags has ample time to thoroughly saturate or impregnate all portions of the rag pieces before the latter reach the rag-pulling machinery, thus placing the rags 95 in the best condition to be operated upon for producing long and desirable fibers, while at the same time a force-feed, such as steam, is not required.

Heretofore a perforated pipe connected with 100

an oil-vessel and a steam-supply pipe has been located parallel to and next the face of a picker-cylinder, between the latter and the traveling rag-carrier and feed-rollers, for steaming the rags and supplying oil thereto by the pressure of the steam at the point where the rags are acted upon by the picker-cylinder, and after the rags have passed the rag-carrier and feed-rolls; but such is not my invention. In another instance heated oil has been forced upon wool as the latter passes from a picker-cylinder to the wool-room, through the medium of an oil-tank having a top discharge-pipe and a steam-inlet pipe, the steam serving to heat the oil and also to force the latter out through the discharge-pipe upon the wool as it leaves the discharge-spout of the picker or cleaner; but neither is such my invention. A cylinder having a row of nozzles has also been used to deliver oil into a series of tubes leading to the fire-box of a boiler-furnace for burning oil; but that is not my invention.

Having thus described my invention, what I claim is—

1. An apparatus for oiling rags on a support which carries them to a rag-pulling machine, consisting of an oil-holding tank, a horizontal cylinder extending across the lower portion of one side of the tank and provided with a row of depending nozzles to overhang the rag support, a series of lateral pipes extending from the cylinder through the lower portion of one side wall of the oil-tank to support the cylinder and place it in communication with the tank, and a regulating-valve in each pipe, substantially as described.

2. The combination, with a rag support for carrying rags to a rag-pulling machine, of an oil-tank located above said support, a horizontal cylinder extending across one side of the oil-tank at the lower portion thereof and provided with a row of depending nozzles overhanging the rag-support, and a series of lateral pipes extending from the cylinder through

the lower portion of one wall of the oil-tank, 45 substantially as described.

3. The combination, with a rag-support for carrying rags to a rag-pulling machine, of an oil-tank located above said support, a horizontal cylinder extending across one side of the oil-tank at the lower portion thereof and provided with a row of depending nozzles overhanging the rag-support, a series of lateral pipes extending from the cylinder through the lower portion of one wall of the oil-tank and each having a regulating valve, and a glass oil-gage connected with the upper and lower portions of the oil-tank, substantially as described.

4. The combination, with a support for carrying rags to a rag-pulling machine, of an oil-tank, A, for containing heated oil, having a jacket, B, and an intervening filling, C, of non-conducting material, for keeping the oil warm, a horizontal oil-distributing cylinder or pipe 65 having a line of depending oil-dropping nozzles, and valved pipes connecting the distributing cylinder or pipe with the interior of the tank, substantially as described.

5. An oil-distributing apparatus for supplying oil to rags in their passage to a rag-pulling machine, consisting of an oil-tank, A, having a jacket, B, and an interposed filling, C, of non-conducting material, for keeping the oil warm, and a series of oil-dropping nozzles in communication with the oil-tank, for supplying the oil in drops in a transverse path across the rags in their passage to the rag-machine, substantially as described.

In testimony whereof I affix my signature in presence of two witnesses.

CHARLES WILCOCK.
